UNITED STATES PATENT OFFICE.

VICTOR MAUCK, OF NORRISTOWN, PENNSYLVANIA.

CONTAINER AND PROCESS FOR FORMING THE SAME.

Application filed August 22, 1922. Serial No. 583,539.

To all whom it may concern:

Be it known that I, VICTOR MAUCK, a citizen of the United States, residing at Norristown, in the county of Montgomery and State of Pennsylvania, have invented a certain new and useful Improvement in Containers and Processes for Forming the Same, whereof the following is a specification, reference being had to the accompanying drawings.

My invention is particularly applicable to sheet metal cans used in transportation and storage of dairy products. For instance, such cans as are used by wholesalers to deliver ice-cream to retailers, and used by the latter to contain such products while they are being dispensed; the emptied cans being thereafter returned to the wholesalers to be refilled and again distributed. Of course, such cans must be extremely durable to withstand the rough handling and wear to which they are inevitably subjected and as such containers are retained in iced salt water to preserve their contents, their bodies must be permanently liquid tight, and also adapted to be substantially hermetically sealed by closures which may be instantly opened and shut, to facilitate dispensation of their contents. Of course, such containers should not have any internal corners or recesses or joints which cannot be readily cleaned of every vestige of their contents, by mechanical means, for such products readily and rapidly decompose. Moreover, as it is customary to pack such containers in ice and salt water within wooden tubs which are only a few inches larger in diameter than the outside diameters of such containers; I find that it is highly desirable to so construct and arrange such a container that its exterior has no enlargement or projection capable of catching in the ice in which the containers are packed; for it is necessary to remove such containers from their ice packings in the vehicles in which they are transported for delivery to customers, and the pieces of ice in which they are packed melt to the precise configuration of the containers, so as to fit against the same so tightly that if there is the slightest projection at the bottom of the container, it catches in the ice and spills the latter upon the floor of the vehicle when the operator endeavors to remove the container from the tub. Furthermore, an essential step in the manufacture of some containers of the prior art is the filling with solder of all crev-

ices between the bottom and side walls of the containers, in an endeavor to render the surfaces of such containers smoother than they would otherwise be. However, I find that the use of solder in any portion of such a container is highly objectionable, for the reason that such containers must not only be coated with pure tin, but must be repeatedly retinned, and, in the operations of tinning and retinning such containers, solder elements of the structures fuse off in the molten tin bath and render the tin unfit for coating, because of the mixture therewith of the different metallic elements of the solder.

Therefore, the object and effect of my invention is to provide containers having the characteristics above contemplated, and particularly to provide methods and means for economically forming the joints between the bodies and the bottoms of such cans as to avoid the disadvantageous projections aforesaid.

My invention includes the various novel features of construction, arrangement and procedure hereinafter specified, and particularly such methods and means as to render the exterior line of junction between the bottom and side walls of such containers substantially flush and continuous with the outer cylindrical circumferences of the containers, so that it is unnecessary to employ solder in their construction.

In said drawings; Fig. I is an elevation, partly in section, of a container embodying my invention.

Fig. II is a fragmentary top plan view of the structure shown in Fig. I.

Fig. III is a fragmentary inverted plan view of said structure.

Fig. IV is a perspective view of a sheet metal cylinder which is the blank from which the body of the container shown in Figs. I to III inclusive is formed.

Fig. V is a diametrical sectional view of a bottom plate, adapted to be fitted in the lower end of the cylindrical blank shown in Fig. IV, in the process of forming the container shown in Fig. 1.

Fig. VI is a diametrical sectional view of a ring of sheet metal which is the blank adapted to form the flange to support and seal the lid closure on said container body.

Fig. VII is a diametrical axial sectional view of said container body, flange ring and bottom plate, showing the same supported upon opposite spinning mandrels.

Fig. VIII is a fragmentary axial sectional

view of said container body and bottom plate, similar to Fig. VII, but showing the rim of the bottom plate partially spun over the bottom of the container body.

5 Fig. IX is a fragmentary sectional view, of substantially full size, corresponding with the upper left-hand corner of Fig. VII, and showing the configuration of the inner end of the expanding and supporting mandrel which supports said bottom plate.

10 Fig. X is a fragmentary sectional view of the same parts shown in Fig. IX, but with the bottom edge of said body pressed inwardly to receive the chime reinforcing ring.

15 Fig. XI is a fragmentary sectional view of the same parts shown in Fig. X, with the addition of the chime reinforcing ring, and with the margin of the bottom plate spun parallel with the cylindrical outer surface 20 of the can body.

25 Fig. XII is a fragmentary sectional view of the same parts shown in Fig. XI, but with the joined portions of the bottom plate and said can body pressed inwardly to the final form shown in Fig. I.

30 Referring to Fig. I; the can body 1 has a removable lid closure 2 conveniently provided with the rigid handle 3; said handle having its opposite ends 4 welded to the top of said closure 2. Said can body 1 is formed of a rectangular primarily flat sheet of metal, conveniently low carbon steel, which is first bent to the cylindrical blank form 6 shown in Fig. IV and then united at its 35 abutting edges 7 conveniently by an electric welding operation, to form a blank from which the body of a can such as shown in Fig. I is formed. A ring 9 of sheet metal, such as is shown in Fig. VI constitutes a blank from which may be formed the flange ring 11 as a fixture upon said can body 1, to support said lid closure 2, as shown at the right-hand side of Fig. I, and thus substantially hermetically seal the joint between the 40 bottom end of said closure and the can when in the position shown in said figure.

45 Said flange ring blank 9 is pushed upon said cylindrical can blank 6 until its upper edge is flush with the top of the latter, and the expanded skirt 12 of said ring blank 9 is then pressed inwardly, against said blank 6, until it is curled to form the toric bead 13 indicated in Fig. I. Although that pressing operation constricts said ring bead 13 upon said can blank 6; I prefer to subsequently slightly expand said can blank 6 within said flange ring 11, slightly stretching the metal of both said parts, to insure that they shall thereafter remain in intimate contact. Such expansion is conveniently effected by thrusting the mandrel 18 into said blank 6, as indicated in Fig. VII.

50 During the aforesaid operation of forming said bead 13 upon the top of said can blank 6, any irregularities in the intended

55 circular form of the lower edge of said blank 6 are corrected by pressing it upon a suitable die; so that said blank 6 will readily fit over the cylindrical portion 19 of the bottom plate 20, as shown in Fig. VII.

60 Said bottom plate 20 is also formed from primarily flat sheet metal, by pressing operations which first cut a circular disk of said metal and then distort it to the cylindrical form shown in Fig. V. It is to be particularly noted that the circumferential edge 21 of said cylindrical portion 19 of said bottom plate 20, which is presented upwardly in the can against the inner face of the cylindrical wall of the latter, as shown in Figs. I and VII, is substantially sharp so that the interior of the container is smoothly continuous at the junction of said bottom plate 20 with the can body 1.

65 The primarily cylindrical bottom edge of said body 6, and said cylindrical portion 19 of the bottom plate 20 are then inwardly converged to the configuration shown in Figs. I and IX to form an annular groove 23 around said converged portion of the can body 6, in a plane at right angles to the axis of said body, and of less diameter than the main portion of said body 6. I find it convenient to thus distort said bottom edge of the can body 6 and the bottom plate 20 while 70 spinning them together upon the mandrel 25 under pressure in opposition to said mandrel 18, while said mandrels 18 and 25 are rotated in coaxial relation, as indicated in Fig. VII, and by means of a roller 26 having the annular flange 27, the perimeter of which is substantially the configuration desired for said groove. It may be observed that said mandrel 25 has an annular recess 29 at the region where it is desired to thus 75 distort said can body 6 and bottom plate 20, so that said parts may be inwardly converged while supported in coaxial relation by said mandrel 25.

80 Thereupon, a chime reinforcing ring 30, preferably of toric configuration, and conveniently formed of a primarily cylindrical wire, is seated in said groove 23 and, thereafter, the bottom plate flange 31 is bent outwardly over said ring 30, conveniently while spinning it upon said mandrel 25 and by means of the cylindrical body portion of said spinning roller 26. It may be observed, with reference to Fig. XI, that said flange 31 of the bottom plate which is thus bent to cylindrical form exterior to said ring 30 is at first of substantially larger circumference than said can body 6. However, the final step in the process of forming the bottom joint of said container shown in Fig. I, is to press said flange inwardly so as to be substantially continuous with the outer circumference of said body 6, as in Figs. I and XII. I find it convenient to also effect that 85 step in the operation by means of the cylind-

drical portion of said spinning roller 26, while spinning said can body 6 upon said mandrels 18 and 25, as in Fig. VII.

- Although I prefer to thus include a distinct reinforcing element 30 in the chime of the container, as above described; it is to be understood that reinforcing elements of different forms may be employed, and that joints otherwise constructed in accordance 10 with my invention may be formed without the inclusion of any such reinforcing elements, and yet have the advantage of the substantially smoothly continuous and solderless construction above contemplated.
- 15 Therefore, I do not desire to limit myself to the precise details of construction, arrangement and procedure herein set forth, as it is obvious that various modifications may be made therein without departing 20 from the essential features of my invention, as defined in the appended claims.

I claim:

1. In a container, the combination with a cylindrical tubular body, having an outwardly extending annular closure supporting flange adjacent its top, and an inwardly converged portion adjacent the bottom thereof, and having its bottom edge curved outwardly, to form an annular groove in said body in a plane at right angles to the axis of said body; both said inwardly and outward curved regions of said body being of less diameter than the main portion of said body; of a chime reinforcing ring, of toric 25 configuration, formed of a cylindrical wire, seated in said groove at the lower end of said body; a bottom plate for said container having a cylindrical portion fitted in said body and a portion extending transversely 30 to said body, said cylindrical and transversely extending portions of said bottom plate forming a sharp cornered annular ridge abutting the inner surface of said body, whereby a smoothly continuous curved 35 surface is formed upon the interior of said container at the junction of said bottom plate and body; said bottom plate having a cylindrical flange upturned exterior to said body, forming a substantially continuous cylindrical surface therewith.

2. In a container, the combination with a cylindrical tubular body, having an inwardly converged portion adjacent the bottom thereof, and having its bottom edge curved outwardly, to form an annular groove in said body in a plane at right angles to the axis of said body; both said inwardly and outwardly curved regions of said body being of less diameter than the main portion of said body; of a chime reinforcing ring, of toric 55 configuration, seated in said groove at the lower end of said body; a bottom plate for said container having a cylindrical portion fitted in said body and a portion extending transversely 60 to said body, said cylindrical and

and transversely extending portions of said bottom plate forming a sharp cornered annular ridge abutting the inner surface of said body, whereby a smoothly continuous curved surface is formed upon the interior 70 of said container at the junction of said bottom plate and body; said bottom plate having a cylindrical flange upturned exterior to said body, forming a substantially continuous cylindrical surface therewith.

3. In a container, the combination with a cylindrical tubular body, having an inwardly converged portion adjacent the bottom thereof, and having its bottom edge curved outwardly, to form an annular groove in said 80 body in a plane at right angles to the axis of said body; both said inwardly and outwardly curved regions of said body being of less diameter than the main portion of said body; of a chime reinforcing ring, of toric 85 configuration, seated in said groove at the lower end of said body; a bottom plate for said container having a cylindrical portion fitted in said body and a portion extending transversely to said body; said bottom plate 90 having a cylindrical flange upturned exterior to said body, forming a substantially continuous cylindrical surface therewith.

4. In a container, the combination with a cylindrical tubular body, having an inwardly converged portion adjacent the bottom thereof, to form an annular groove in said body in a plane at right angles to the axis of said body, of less diameter than the main portion of said body; of a chime reinforcing ring, seated in said groove; a bottom plate for said container having a cylindrical portion fitted in said body and a portion extending transversely to said body, said cylindrical and transversely extending 100 portions of said bottom plate forming a sharp cornered annular ridge abutting the inner surface of said body, whereby a smoothly continuous curved surface is formed upon the interior of said container 105 at the junction of said bottom plate and body; said bottom plate having a cylindrical flange upturned exterior to said body, forming a substantially continuous cylindrical surface therewith.

5. In a container, the combination with a cylindrical tubular body, having an inwardly converged portion adjacent the bottom thereof, to form an annular groove in said body in a plane at right angles to the axis of said body, of less diameter than the main portion of said body; of a chime reinforcing ring, seated in said groove; a bottom plate for said container having a portion fitted in said body and a portion extending transversely to said body; said bottom plate having a cylindrical flange upturned exterior to said body, forming a substantially continuous cylindrical surface 120 therewith.
